UNITED STATES PATENT OFFICE.

ELBRIDGE J. STEELE, OF WOLCOTTVILLE, CONNECTICUT, ASSIGNOR TO TURNER, SEYMOUR & JUDDS, OF SAME PLACE.

DESIGN FOR CASTER-RINGS.

Specification forming part of Design No. 5,275, dated September 19, 1871.

To all whom it may concern:

Be it known that I, ELBRIDGE J. STEELE, of Wolcottville, in the county of Litchfield and State of Connecticut, have invented or produced a new and original Design for Caster-Rings; and the following is declared to be a correct description thereof.

This design relates to the ornamental ring surrounding the lower end of the chair or other leg to which the caster-wheel and pivot are applied.

The general configuration of said ring is that of a slight cove, *a*, and a shoulder at *b*.

The ornament placed upon the surface is that of a leaflet and scroll-rib, as represented.

I claim—

The design of the caster-ring, as described and represented.

Signed by me this 18th day of July, A. D. 1871.

ELBRIDGE J. STEELE.
